By Howard F. Raschick
his Attorney.

Patented Mar. 13, 1928.

1,662,166

UNITED STATES PATENT OFFICE.

CHARLES T. RASCHICK, OF ST. PAUL, MINNESOTA.

CHECK HOLDER AND CUTTER.

Original application filed February 2, 1920, Serial No. 355,572. Divided and this application filed June 23, 1921. Serial No. 479,803.

My invention relates to a check holder and cutter which is particularly designed to hold a pad of checks in a convenient manner so that the checks can be removed from the stub of the pad as they are desired for use and punched by the cutter associated therewith without requiring an extra punch for making indications by serrations or cutaway portions in the checks of the pad.

10 An object of the invention is to provide notches along the sides of the back of the cutter so that the slideable member having the cutter mounted thereon may be readily removed from the device.

15 A still further object is to provide a clamp for said cutter having spring means adapted to be secured to the body of said clamp to press the book of checks upwardly against the clamping member connected with said check holder.

20 A further object of my invention is to provide a pocket associated with the cutter to enclose and hold the clippings from the checks, and the cover of the pocket being freely slideable so as to move the same by gravity into closed position when the holder hangs by the holding loop on the operator's person, it also being a feature of the invention to provide means whereby the checks normally hold the cover of the pocket in closed position.

In the drawings forming a part of this specification:

Figure 1 is a perspective view of my check holder and cutter as it would appear in use holding a pad of checks.

Fig. 2 is a cross sectional side elevation of my device.

Fig. 3 is a perspective view of the upper portion of my device.

Fig. 4 is a cross section on the line 4—4 of Fig. 2.

Fig. 5 is a perspective view of the lower portion of my device, illustrating an alternative form of cutting punch with the cover of the pocket in open position.

This application is a division of my application for check holder and cutter filed February 2, 1920, bearing Serial No. 355,572.

50 In the drawings, A represents my check holder and cutter which is designed to hold a pad of checks B, which are stapled together on one end in the ordinary well-known manner with the stub ends 10 of the 55 checks held between the gripping face or

plate 11 and along the back 12 of the holder A.

The face 11 is formed as an extension from the back 12 and extends approximately parallel thereto, being connected with the same 60 by the upper end portion 13, to which is attached the holding loop 14 by the cleats 15, or in any other suitable manner. The holding loop 14 is engaged by a hook, chain or other suitable means, not shown, for 65 attaching the holder A to the belt of a waitress or clerk in the use of the same, while the body portion or back 12 hangs free, either extending in a downward direction or so that it can be readily engaged and elevated to remove one of the checks 16 from the pad B. The checks 16 are perforated or otherwise suitably scored at 17 to allow them to be easily disengaged from the stub portion 10 of the pad. 70

75 Engaging teeth 18 are formed on the front edge of the plate 11, while a spring 19, which is attached to the back 12, tends to hold the pad B into engagement with the teeth 18. Guide flanges 20 are formed depending from the engaging plate 11, while reinforcing flanges 21 project upward from the back 12 to form side engaging members to hold the pad in line in the holder A with its checks extending along the back 12. 80

85 A cutter punch C is carried by the end of the holder A opposite to the loop 14 and is provided with a cutting tongue 22, which is formed of spring steel, or some other suitable material, which is attached to the plate 90 23 at 24 to the upwardly projecting flange 25, which extends as a portion of and approximately at right angles to the body portion of the plate 23. The plate 23 forms the back and body portion of the cutter punch 95 C and also the cover for the pocket E which is formed as an integral portion and extension of the back 12.

The plate 23 is held freely slideable to the back 12 by the inturned flanges 26, see Figure 4, which engage along the lower longitudinally extending edges of the back 12, while the back 12 is cut away or formed with longitudinally extending recess portions 27, to form a narrow portion 28 along the back 12 of the holder. This narrow portion 28 allows the free engagement of the checks 16 particularly when the pad B becomes practically used up and only a few checks remaining in the pad, and also allows the 105 110

cutter plate 23 to be removed by depressing the tongue shoulder 29, which is formed by cutting a portion out of the back 12 and bending it upward to normally engage 5 against the flange 25 of the cutter to limit the backward movement of the same. This construction allows a new cutter tongue and blade to be provided for the holder B at any time, should it be found necessary to do so 10 and this feature is of great importance in the practical development of my invention. Stiffening flanges 30 are formed extending longitudinally in the portion 28 to strengthen and add to the rigidity of that portion 15 of the back, to properly support the elements of the holder.

The plate 23 is formed with an upwardly inclined end 31, which extends at an obtuse angle from the body portion of the plate and 20 forms a cover for the upwardly projecting portion 32 of the pocket E. An opening 33 which is of the same shape and of a slightly larger dimension than the cutting end or point 34 of the cutting tongue 22, is formed 25 in the angularly extending portion 31 of the plate 23, while the rear portion of the opening 33 extends into the body portion of the plate 23 and is of any suitable shape. In this construction the cutter tongue of the 30 punch C is formed with an enlarged finger engaging portion 35, which limits the downward movement of the cutter tongue 22 in the opening 33.

A loop member 36 is secured to the angular portion 31 through which the pointed cutting end 34 of the tongue 22 extends. The loop 36 forms a guard and limits the upward movement of the cutting end of the tongue 22 as it prevents the sharp pointed 40 end 34 projecting or being bent upward into a dangerous position. In a device of this kind it is necessary that no portions of the same be exposed upon which the operator can be easily injured and the guard 36 will 45 protect the point 34 while also the upwardly projecting end 31 of the cover forms a natural guard for the pointed cutting end 34. The loop 36 also forms a stop or gage for the checks 16 to limit the depth of the cut 50 or cutter punch C in the checks.

In operating the cutter punch C a ticket or check 16 taken from the pad B is inserted with its edge against the gage 36 and a portion of the check positioned between the 55 point of the cutter and the upper end of the opening 33 in the portion 31 of the plate. As the cutting tongue 22 is depressed, the point 34 will first pierce the check and then shear a V-shaped portion out of the same at 60 a point on the check to indicate the amount of a purchase, while the portion of the check clipped or punched from the body of the same will be deposited into the chamber 38 of the pocket E and retained therein until 65 the pocket is opened by pulling the punch

with its plate 23 backward to draw the portion 31 back sufficiently to open the same.

The plate 23 with the portion 31 is held freely slideable by the flanges 26 to the back 12 of the holder and thus when the holder 70 is in use and the pocket E hangs downward the plate 23 would move or be held by gravity into closed position. However, the checks 16 of the pad B engage against the flange 25 and form a stop to hold the cover 75 of the pocket E normally in closed position. In this manner the flange 25 performs two functions, as it also tends to hold the pad B in place along the back 12. The cover of the pocket can be opened, however, even with 80 the pad of checks B in place in the holder, by pulling backward against the checks to bend them sufficiently to allow the cover to move into open position.

In Figure 5 a cutter punch F is illustrated, 85 having a cutting tongue 39 formed out of the body portion of the plate 23, the pointed end 40 of which coincides with the similar shaped opening 41 formed in the angularly disposed end 31 of the plate 23. The functions of this cutter punch are identical to that performed by the cutter punch C and this punch operates to cut a portion from the checks to indicate the amount of a purchase and deposit it in the pocket E formed 95 on the lower end of the back 12.

In the operation of a device of this nature the general construction of the holder is practically indestructable with ordinary use and care but it is very desirable to have a replaceable cutter, as through continued use the cutter is apt to become dull and owing to the simple, inexpensive construction of my device a new cutter can be quickly and easily attached to the holder by sliding the 100 plate 23 backward, when the pad of checks B is removed from the holder and the spring tongue 29 depressed to allow the engaging flanges 26 to move back to the narrowed portion 28 of the back 12, whereupon the 105 flanges 26 are disengaged from the back to release the cutter punch plate and cover for the back 12. This feature adds materially to the practical nature of my device.

The inclined or angularly positioned portion 31 of the plate 23 permits the cutter tongue 22 to operate easily to make a clean-cut notch in the tickets or checks and this construction does not require the close fit between the male and female portions of 110 the cutter punch as are necessary in the ordinary punching devices.

The stub 10 of the pad B which is left clamped between the back 12 and the plate 11 after all of the tickets or checks 16 have 115 been removed can be easily removed either by engaging the same through the opening 42 formed in the plate 11 to depress the stub and free it from the teeth 18 so that it can be pulled out and discarded or the stub 120

can be engaged between the flanges 20 and 21 on either side of the same and released by depressing against the spring 19. A new pad of checks can then be inserted in the 5 holder while the back of the same holds the spring 19 depressed, the spring 19 holding the stub of the pad into engagement with the teeth 18 and plate 11 while the leaves or checks of the pad form a stop to hold the 10 cover plate 23 in closed position on the pocket E.

The positioning of the pocket E at the opposite end to the holding loop 14 is an 15 essential feature of the construction of my device, as it allows the cutter punch V to be operated without removing the holder A from the chain or hook which holds it by the loop 14 to the waitress or clerk's belt, it being easy for the clerk or waitress to 20 engage the end of the holder carrying the pocket and raise it sufficiently to readily see and operate the cutter punch.

In accordance with the patent statutes I 25 have described the principles of operation of my invention, together with the apparatus which I now consider to represent the best embodiment thereof, but I desire to have it understood that the construction shown is only illustrative and that the invention 30 can be carried out by other means and applied to uses other than those set forth within the scope of the following claims.

I claim:—

1. A check holder comprising a back, an 35 over-lapping end formed on said back for enclosing the stub end of a book of checks, a pair of raised looped members cut out of

said back, a U shaped spring clamp adapted to be secured to said back within said looped members, said spring normally extending 40 out of the plane of said back to press the book of checks against said over-lapping end.

2. A check holder comprising a supporting back for a pad of checks, a clamping plate fixedly connected to said back and spaced therefrom and resilient means for holding the stub of the pad against said clamping plate, said means being secured to 45 said back by means of two looped portions struck up from said back.

3. A check holder comprising a back, a member slidable along said back at one end thereof, a receiving member positioned at the other end of said back adapted to receive a pad of checks, means consisting of an enlarged portion in said back for limiting the movement of said slidable member and means at right angles to said back upon 50 said slidable member for engaging the other end of said pad of checks to hold the same in place.

4. A check holder comprising a back, a member fixedly secured to said back in spaced relation thereto, for receiving the stub end of a book of checks, a resilient member secured by looped portions in said back extending longitudinally along said back having a portion raised out of the plane of said back and adapted to engage 55 the stub end of the book of checks and force the same into engagement with said member.

In testimony whereof I affix my signature.

CHARLES T. RASCHICK.
